UNITED STATES PATENT OFFICE.

GEORGE SMART, OF ST. LOUIS, MISSOURI, ASSIGNOR TO HIMSELF AND
DANIEL B. TAYLOR, OF SAME PLACE.

VENTILATOR.

SPECIFICATION forming part of Letters Patent No. 280,526, dated July 2, 1883.

Application filed October 6, 1882. (No model.)

To all whom it may concern:

Be it known that I, GEORGE SMART, of St. Louis, in the county of St. Louis and State of Missouri, have invented a new and Improved 5 Ventilator, of which the following is a full, clear, and exact description.

The object of my invention is to provide a new and improved portable ventilator, which can be erected for use and taken down very 10 easily, and can be adjusted as may be desired.

The invention consists in a ventilator formed of an elbow provided with an adjustable mouth and a valve, which, when closed, admits the air into the room, and which, when opened, 15 permits the air to pass off at the elbow.

The invention also consists in a device for adjusting the mouth of the ventilator for holding the ventilator in place, and in other parts, as will be fully described and set forth herein- 20 after.

Reference is to be had to the accompanying drawings, forming part of this specification, in which similar letters of reference indicate corresponding parts in all the figures.

25 Figure 1 is a side elevation of my improved ventilator, showing it erected for use. Fig. 2 is a front elevation of the same. Fig. 3 is a longitudinal sectional elevation of the same.

An elbow, A, has its vertical arm A' made 30 tubular, and its other arm, A², increases in diameter toward the outer end, and to the same an upwardly-projecting U-shaped frame, B, is hinged at b, to swing to the position shown in dotted lines, Fig. 3, to which frame a piece 35 of fabric, C, is attached, which is also attached to the inner end of the arm A², as shown. The said arm A² is provided in its top with an opening, D, at its inner end, the said opening being directly in front of the line of contact of the 40 elbow-arm A² and the lower edge of the fabric C. A bar or rod, E, is pivoted to the U-shaped frame B, and by means of the same the said frame can be adjusted at the desired inclination. The bar E has apertures a, through 45 which a stud, d, on the elbow A is passed, whereby the frame B can be locked at the desired inclination. The mouth of the ventilator is thus made adjustable, and its size can be increased or decreased, as circumstances 50 may require. If desired, the free end of the

bar E can also be secured to a window or door frame. The elbow A is provided at its angle with an aperture which can be closed by a swinging cap-valve or curved plate, G, hinged to the elbow. A cord, H, attached to the 55 outer edge of the cap G, passes through loops g g on the elbow. By pulling on this cord the cap or valve G is swung over the opening in the elbow, which is thus closed. A cord, J, attached to the cap G, is used to open the same. 60 A flexible conductor or tube, K, preferably made of fabric, is attached to the vertical arm of the elbow, and conducts the air into the apartment. Two parallel bars or rods, M, project down from the lower edge of the vertical arm of the elbow, and are used to hold the ventilator in the desired place. For instance, they are passed over a window-frame, shutter, door, &c., and they will hold the ventilator 65 on the said door, shutter, &c. The mouth of 70 the ventilator can easily be adjusted, as stated above, to catch and admit a greater or less quantity of air, and by opening the cap G the air can pass direct through the horizontal arm A² of the ventilator. If the cap G is closed, 75 the current of air passes down through the tube K into the room or apartment, and will not create a disagreeable draft.

Having thus described my invention, I claim as new and desire to secure by Letters Patent— 80

1. In a ventilator, the combination, with the elbow A, of the hinged frame B at the front end of the same, and the fabric C, attached to the said frame and to the elbow A, substantially as herein shown and described, and for 85 the purpose set forth.

2. In a ventilator, the combination, with the elbow A, of the hinged frame B at the front end of the same, the fabric C, attached to the frame B and to the elbow A, and the pivoted 90 rod or bar E, substantially as herein shown and described, and for the purpose set forth.

3. In a ventilator, the combination, with the elbow A, of the hinged frame B, the fabric C, the bar E, provided with apertures a a, and 95 the pin d on the elbow A, substantially as herein shown and described, and for the purpose set forth.

4. In a ventilator, the combination, with the elbow A, of the hinged frame B, the fabric C, 100

and the hinged cap or valve G, substantially as herein shown and described, and for the purpose set forth.

5. The combination, with the horizontal and vertical pipes of a ventilator, of the elbow A, having a hole horizontally through it, the cap or valve G, hinged to it to cover said hole, the cords H J, secured to said cap, and the loops g on the elbow to support the cord H, where-
10 by a portion of the air coming in at the cowl may be allowed to pass out at the elbow, as shown and described.

6. The combination, with the elbow A, joining the horizontal and vertical arms of a venti-
15 lator, of the bars or rods M, secured thereto and adapted to be fastened at their other ends, as described, whereby the ventilator is sup-
ported, as set forth.

GEORGE SMART.
